UNITED STATES PATENT OFFICE

ROBERT F. McCARTHY, OF WEBSTER GROVES, MISSOURI, ASSIGNOR TO INTERNATIONAL SHOE COMPANY, OF ST. LOUIS, MISSOURI, A CORPORATION OF DELAWARE

SHOE

Application filed December 24, 1928. Serial No. 328,211.

This invention relates to shoes and has special reference to means for holding the shoe properly fitted on the foot and to prevent the shoe from slipping at the heel.

5 My invention comprises elastic bodies secured between the counter and the lining near the rear portion of the shoe upper and forming fillers to fit more closely against the sides of the foot of the wearer near the heel so as 10 to prevent the shoe from slipping.

An object of the invention is to provide the above described construction in a shoe to prevent the shoe from slipping and to obtain other advantageous results including those 15 herein described and otherwise made apparent, reference being made to the drawing in which.

Fig. 1 is a perspective view of a shoe embodying the present invention.

20 Fig. 2 is a cross sectional view of the rear portion of the shoe showing the elastic bodies in position between the lining and the counter.

Figs. 3 and 4 are views showing the inner side and an edge view, respectively, of one 25 of the elastic bodies.

The shoe in which the present invention is shown is of the low type, the heel portion comprising an upper 1, a counter stiffener 2 of comparatively stiff material contacting 30 with the inner side of the heel portion of the upper, and a lining 3 secured to the inner surface of the counter. Heretofore, efforts have been made to prevent the heel portion of the shoe from slipping relative to the foot 35 of the wearer. Such efforts have included the provision of frictional devices or roughened surfaces on the inner side of the lining, and other expedients. My present invention constitutes a departure from previous

40 devices of this kind by providing elastic bodies between the counter and the shoe lining and having convexed inner surfaces to fit within the cavities at the sides of the heel of the foot of the wearer. Thus at each side 45 of the heel portion of the shoe is an elastic body 4 of soft rubber or equivalent material. These bodies 4 are secured between the counter 2 and the lining 3 so that their convexed inner surfaces cause the lining to form 50 similarly inwardly convexed extended por-

tions 5 arranged in such relationship that they extend into the cavities at the sides of the tendons below and rearwardly of the ankle joint and above the sole of the heel of the foot of the wearer. The distance transversely between the surfaces of the extensions 5, therefore, is considerably less than the distance transversely between the surfaces of the lining below said extensions so that the broad portion of the heel of the foot 55 of the wearer comes below the extensions 5 while said extensions 5 fit within the cavities above the broad heel portions of the foot. Being of very soft rubber or equivalent material, the bodies 4 will not cause any discomfort but will hold the shoe more perfectly fitted on the foot and will prevent the heel portion of the shoe from slipping from the foot of the wearer or the foot of the wearer 60 from slipping from the shoe.

As shown in Fig. 1 these extensions 5 do not extend around the rear portion of the shoe but are widely separated so as to fit only 65 within the cavities at the sides of the heel.

70 Preferably the bodies 4 are glued or cemented or otherwise secured to the counter without the use of any metallic fastening devices, as it is desirable to maintain complete elasticity. The lining need not be secured to the inner surface of the bodies 4.

75 The construction and arrangement may be varied within equivalent limits without departure from the nature and principle of the invention.

80 What I claim and desire to secure by Letters Patent is:—

85 1. In a shoe, a shoe upper, a counter stiffener secured against the inner side of and shaping and holding shaped the heel portion 90 of the upper, a pair of elastic and soft bodies having substantially flat outer walls secured to opposite sides of said counter stiffener and having substantially oval edges and convexed inner walls, said bodies being secured 95 to said counter stiffener wholly below the upper edge of said counter stiffener and above the sole of the shoe, and a lining secured to the inside of the sole and fitting against and covering said convexed inner 100

surfaces of said bodies and having its upper edge attached to the heel portion of the shoe above said bodies.

2. In a shoe, a shoe upper, a counter stiffener secured against the inner side of and shaping and holding shaped the heel portion of the upper, a pair of elastic and soft bodies having substantially flat outer walls secured to opposite sides of said counter stiffener and having substantially oval edges and convexed inner walls, said bodies being secured to said counter stiffener wholly below the upper edge of said counter stiffener and above the sole of the shoe, and a lining secured to the inside of the sole and fitting against and covering said convexed inner surfaces of said bodies and having its upper edge attached to the heel portion of the shoe above said bodies, the distance transversely between the inner surfaces of said lining extending over said bodies being shorter than the distance between the lining at opposite sides of the shoe below and above said bodies.
